UNITED STATES PATENT OFFICE

VINCENT N. NICOSIA, OF HOUSTON, TEXAS.

PERMANENT HAIR WAVING AND CURLING PAD.

Application filed August 22, 1927. Serial No. 214,768.

This invention relates to improvements in curling pads or sachets for use in permanent hair waving. The class of pad or sachet relates further to such contrivances or devices as are used in conjunction with the standard hair curling and hair waving machines, such machines being provided with a number of heating elements for waving the hair. To each of these elements is 10 cured a plurality of curling irons of standard pattern. In practice the hair is first wrapped around the curling or waving element and the pad or sachet wrapped around both the waving element and the 15 hair, so as to embrace both the hair and the element.

By the improved curling pads as presented in this invention, the time of operation is reduced at least 25% and also the danger 20 of burning the hair, because owing to the foil material which is employed the exact time the waving is completed is unerringly indicated by the foil attaining when heated a pinkish hue.

25 The invention will be more clearly understood from a perusal of the following detailed description, taken in connection with the accompanying drawing forming part hereof and in which:

30 Figure 1 is a top plan view of the pad or sachet, the pad being spread out ready to be applied.

Figure 2 is a cross-sectional view taken along the line 2—2 of Figure 1.

35 Figure 3 is a side elevational view of the pad wrapped around the hair and waving or curling element ready for application of the heat; and

40 Figure 4 is an enlarged partial view of the pad, the absorbent material being broken away to show its arrangement.

Having a more detailed reference to the drawings, 1 denotes a piece of tin foil of preferably oblong shape and which forms the outside of the pad or device when the hair is wrapped ready for application of the heat. Upon the foil is placed a small piece of oiled paper 2 not quite as long as the foil, the purpose of the shorter length being 45 to enable the foil to be twisted more easily and compactly at the ends 3 as shown in Figure 3 in making the seal.

Upon the oiled piece 2 at one side is dis-

posed two folds of absorbent material 4. These folds are enclosed one within the other 55 and then the side edges of the folds, together with the oiled sheet 2, are stitched as at 5 to the foil 1. When the stitch is made, the free ends of the fold are placed on the edges of the oiled piece and the foil, after which 60 the absorbent material is brought over in the manner shown in Figure 2, ready for enclosing the hair and heating element.

Along one side and inwardly from the edge of the oiled piece is a line of adhesive 65 as indicated at 6, so that when the hair is wrapped up the adhesive will cause the oiled piece to adhere to the foil. In addition to this, the ends are twisted as indicated at 70 3 and the pad is securely sealed around the hair 7.

Particular attention is again called to the fact that by the use of the foil the exact time for removing the pad is unerringly indicated, the foil turning a pinkish hue when 75 the waving or curling is completed.

It should be understood, of course, that the pieces forming the pad may be braided or otherwise fastened together, and also that the sizes of the pieces may be varied if desired. Likewise the absorbent material may be used in more folds or less than those shown.

What is claimed is:

1. A wrapper for the purpose of enclosing 85 hair tresses in making permanent waves in hair, comprising a sheet of foil, a sheet of oiled paper, and a plurality of folds of absorbent material, said absorbent material connected at one edge to one edge of the foil 90 and oiled sheet and lapped over upon the oiled sheet in readiness for wrapping around the tress; and said oiled sheet having a marginal adhesive; the ends of said wrapper being twisted at both ends after it is placed 95 around the hair tress to seal the wrapper around the hair.

2. A wrapper for the purpose of enclosing 100 hair tresses in making permanent waves as set out in claim 1, said foil being on the outside of the wrapper and when sufficient heat has been applied to the wrapper, said foil changing to a pinkish hue to indicate the time for removing the wrapper.

In testimony whereof I affix my signature.
VINCENT N. NICOSIA.
